(No Model.)

C. GERHARD.

CRIMPER FOR BOOT OR SHOE PACKS.

No. 364,010.

Patented May 31, 1887.

UNITED STATES PATENT OFFICE.

CHARLES GERHARD, OF MERRILL, WISCONSIN.

CRIMPER FOR BOOT OR SHOE PACKS.

SPECIFICATION forming part of Letters Patent No. 364,010, dated May 31, 1887.

Application filed February 19, 1887. Serial No. 223,198. (No model.)

To all whom it may concern:

Be it known that I, CHARLES GERHARD, a citizen of the United States, residing at Merrill, in the county of Lincoln and State of Wisconsin, have invented certain new and useful Improvements in Crimpers for Boot and Shoe Packs; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to an improved method and means for crimping boot and shoe packs. Heretofore such packs were constructed by the shaping of the leather over the last while moist and holding the same in position till dry by tacks. This process consumed a vast deal of time, and is the source of no end of trouble and vexation.

20 The object of this invention is to lighten the task of and expedite the constructing of such 25 packs.

The improvement consists in having a crimpler of peculiar shape, preferably composed of malleable metal, adapted to fit about the toe portion of a last and hold the leather 30 between it and said last. The leather is placed between the crimpler and last, and is shaped and held to the last by hammering the crimpler. This process conforms both the leather and the crimpler to the last, and when the leather is 35 sufficiently crimped and smooth the hammering ceases and the leather will be held in such position till fixed by the stiffness of the crimpler, which will retain its shape after the hammering or shaping process is stopped. This method 40 dispenses with the use of the tacks as heretofore employed for holding the pack or leather to the last after being shaped, and retains the leather as it and the crimpler is gradually shaped to the last. The crimpler can be used 45 a number of times.

In the drawings, Figure 1 is a plan view of a last, showing a pack partly crimped. Fig. 2 is a bottom perspective view. Fig. 3 is a perspective view of a modified form of crimpler. 50 Fig. 4 is a detail sectional view, parts broken away, on the line xx of Fig. 1. Fig. 5 is a

cross-section of the last, pack, and crimpler on the line yy of Fig. 1. Fig. 6 is a perspective view of the crimpler.

The crimpler A consists of a strip of malleable material, preferably steel or iron, of a length to fit around the toe of a last and extend about half-way on each side thereof. The middle portion is provided with a tongue or lip, a , which is adapted to fit beneath the toe 60 of the last and hold the crimpler against vertical displacement.

In carrying out my invention, the leather B, which is softened by soaking in water, is placed around the last C and bent up about 65 the sides thereof. The heel is shaped in the usual manner by cutting gores therefrom and sewing the seams together, and the toe, which is to be shaped to the last, has the crimpler A fitted thereto and shaped to the last by hammering. Each blow of the hammer presses the crimpler closer upon the leather and retains it in such position, and also brings the leather and crimpler into nearer conformity to the shape of the last. After the shaping process is completed the crimpler is fastened to the last, preferably, by the two tacks b , one driven through openings at each end of the crimpler. The last is set aside till the leather is thoroughly dry, when the pack is complete and 70 ready for use.

Fig. 3 shows a form of crimpler in which the upper edge, a' , near the middle, is provided with a series of slits, which extend a short distance into the body of the strip composing it, to facilitate the shaping of the crimpler about the toe of the last, as will be readily understood. It is possible, however, to shape it by the use of a forge, so that the slits can be dispensed with, and thereby make it more durable.

I am aware that shoe-tips have been made of metal which is composed of a portion to fit about the toe, a flange to extend beneath the insole, and a tongue projected inward from the middle of the flange to be secured to the 95 bottom of the insole. Such tips are essentially different from my crimpler and cannot be used in a similar manner. The essential feature of my construction of crimpler is having the same made of a single strip bent approximately in U-shape form to fit around the toe 100 of the last and having a tongue, only, pro-

jected inward from its lower edge, which tongue acts in opposition to the upper bent edge of the crimper and prevents said edge riding over the toe of the last during the process of shaping the leather blank to the toe of the last. If a flange were provided on each side of the tongue, the blank would be drawn out of shape during the operation of driving the crimper up to the last, inasmuch as the leather upon the sole or near each side of the last would be caught by said flanges, as will be readily appreciated.

Having thus described my invention, what I claim, and desire to secure by Letters Patent, is—

1. The herein-described method of constructing packs, which consists in first placing the leather blank upon the sole portion of the last and turning it up about the sides thereof, then fitting a malleable crimper over the upturned portion at the end of the last, and finally shaping the crimper and leather to the last by hammering upon the crimper, which latter

holds the leather in position until it is conformed to the last, substantially as set forth. 25

2. The herein shown and described crimper for constructing shoe-packs, consisting of a single strip approximately U shape, adapted to fit around the toe of a last and extend about midway on each side thereof, the ends being provided with openings to permit the passage of tacks for securing the crimper to the last, and the upper edge near the middle curved inward and the rapidity of the curve diminished gradually toward said ends, and having a tongue projected inward from the lower edge directly opposite the curved middle or toe portion and adapted to pass under the last, substantially as and for the purpose described. 35

In testimony whereof I affix my signature in presence of two witnesses.

CHARLES GERHARD.
